GRINDING APPARATUS

Alfred E. Hamilton, Pittsburgh, Pa.

Application October 7, 1942, Serial No. 461,121

11 Claims. (CL 51—78)

My invention relates to the art of surfacing by abrasion and polishing, and particularly to the surfacing of sheets and strips. The invention is useful not only in the surfacing of metal, but also the grinding and polishing of other materials, including sheets of the transparent plastic type that may be used as substitutes for glass sheets or plates.

One object of my invention is to provide surfacing apparatus of such form that a billy roll or other element that supports the work against a surfacing roll will automatically be moved toward and from operative position by traveling movement of the work piece.

Another object of my invention is to provide an improved manner of mounting the billy roll and adjusting it with respect to the surfacing roll, with a desired variation in effective resistance which it may offer to the grinding pressures such as result in the use of a yieldable or pneumatic surfacing roll.

Another object of my invention is to provide polishing apparatus of such form that the surfacing elements will not have to be changed or adjusted each time that a change is made in the gage or thickness of the work which is to be surfaced.

A further object of my invention is to provide surfacing apparatus wherein abrasive sleeves can be applied to and removed from their rolls, without the necessity of removing the rolls from the machine.

In the accompanying drawings, Figure 1 is a side view of a surfacing machine; Fig. 2 is an end view thereof, but with the splash shield shown in section; Fig. 3 is an enlarged detailed view of a portion of the apparatus of Fig. 1, partly in section; Fig. 3a is a modification of a portion of the apparatus of Fig. 3; Fig. 4 is a perspective view schematically showing the arrangement of certain of the parts of the apparatus; Fig. 5 is an enlarged view showing the surfacing roll of the other figures partly in section; Fig. 6 is a view showing the manner in which an abrasive sleeve can be slid to or removed from the surfacing roll without dismounting the roll from the machine frame; Fig. 7 is a view showing a modification of the billy roll of the other figures; Fig. 8 is a side view showing the manner in which guide fingers are positioned between the surfacing roll or drum and pinch rollers for advancing sheet material, and Fig. 9 is a plan view of the fingers.

The apparatus is shown as mounted within and upon a base frame 10. A motor 11 is mounted within the frame and has a belt drive con-

nection 12 with the shaft 13 of a surfacing roll 14. This roll may be of any well-known form, but is here shown (Fig. 5) as comprising a hub portion 15 secured to the shaft 13 and carrying a pneumatic drum 16, an abrasive sleeve 17 surrounding the drum 16. This sleeve will carry abrasive grains of desired size, or other surfacing material, depending upon the character of work to be performed, as in the case of my application Ser. No. 380,442, filed Feb. 25, 1941. Also, a suitable degree of air pressure is maintained in the drum from a supply line 18 through a pressure regulator 19, through a passageway 20 in the shaft 13 and a pipe 21. A relief valve 22 will permit exhaust of excess pressure that is developed through heat of grinding or otherwise, as explained in my said application.

Upper and lower bearing elements 24 and 25 respectively, of the radial self-aligning type, are provided for each end of the shaft 13, these bearing elements being detachably connected together by eye bolts 26.

Each of the bearing members 25 is supported upon a pair of pinch roll housings or supporting frames 28, there being two of these housing members at each side of the machine and mounted upon the base frame 10.

For the purpose of wet grinding operations, as where it is desired to prevent overheating of the drum and the material being surfaced, I provide a hood or shield 30 which is pivotally mounted at 31 upon suitable bracket members carried by the housing 28 at one end of the machine. This hood has slots 32 formed in the end plates, so that the lower edges of the end plates or walls can be moved to a plane below the shaft 13. The shield has a spray pipe 33 secured therein by hook bolts 34 and extending throughout the length of the shield. Water is supplied to the spray pipe 33 for discharge against the drum, from any suitable source, through a pipe 35.

The roll shaft 13 is extended at one end as shown in Fig. 2, this extended portion projecting through a post 36 that serves also as a bracket for the pressure regulator 19. A bearing block 37 is vertically slidable in the post 36 and rests upon the shaft 13. A screw 38 has threaded engagement with the upper portion of the post 36 and thrust engagement with the block 37. This screw is operated whenever it is desired to change the roll or replace a worn abrasive sleeve with a new sleeve. To this end, eye bolts 39 (Fig. 1) which hold the bearing member 25 at the opposite end of the machine upon its seat on the pinch roll housing 28, are loosened and swung clear of the

bearing member 25. Thereupon, the hand wheel of the screw 38 is turned to tilt the adjacent end of the shaft 13 downwardly (Fig. 6) and thereby effect raising of the opposite end of the shaft and the bearing member 25. The pipe connections to the shaft will, of course, be flexible to permit this movement. Thereupon the pressure in the pneumatic drum 16 will be reduced to permit sliding of the sleeve therefrom past the bearing member 25 and upon replacement by a new abrasive sleeve, the screw 38 can be turned to restore the shaft 13 and the roll to operative position. This arrangement avoids the necessity for removing the roll from the stand when changing abrasive sleeves.

A pair of pinch rolls 40, 41, shown more clearly in Fig. 4, are mounted in the housings 28 at the entrance end of the machine and a pair of pinch rolls 42, 43 are mounted in the housings 28 at the rear end of the machine. A second pair of rolls 45 are mounted at the entrance end of the machine, and these rolls may simply idle to serve as guide rolls, or may be driven. The housing members 28 at the discharge end of the machine are formed at 46 to support other pinch or guide rolls, or to temporarily support an element (not shown) for grinding an out-of-round pneumatic drum to true cylindrical form.

The upper pinch rolls 41 and 43 are held in engagement with the lower pinch rolls by weighted levers 47 upon which weights 48 are adjustably mounted. The levers 47 are pivoted to ears on the housings 28 and have their lower edges lying within upstanding bifurcated studs 49 that at their lower ends engage with curved blocks 50 that rest upon the shafts of the rolls 41 and 43 (Fig. 1). The bearings for these upper pinch rolls have slight vertical movement in the housings 28 to permit the pinch rolls to adapt themselves to sheets or strips of various thicknesses and to be held in snug driving engagement therewith by the weights 48.

A motor 52 (Figs. 2 and 4) is provided for driving the pinch rolls. The motor operates through reduction gearing at 53 to drive a sprocket chain 54 that passes around a sprocket 55 on the shaft 56 of the pinch roll 40. The shaft 56 at its other end has a sprocket wheel 57 that through a chain 58 drives a sprocket wheel 59 on the shaft 60 of the pinch roll 42. The shaft 56 carries a gear wheel 61 that meshes with a gear wheel 62 on the shaft of the pinch roll 41. Similarly, a gear wheel 63 on the shaft 60 drives the pinch roll 43 through a gear wheel 64.

A billy roll 66 is provided for supporting the sheet or strip material 67 against the grinding pressures of the surfacing roll 14. This roll has a shaft 68 that is supported at its ends in bearings 69. These bearings 69 are supported on a channel-like rail 71 that extends crosswise of the machine and is vertically slidable between the adjacent ends of the pinch roll housings 28, so that as the rail 71 is moved up and down, the bearings 69 and the billy roll 66 will likewise be moved. The bearings 69 are connected to blocks 72 (Fig. 3) which are secured to the rail 71 and are detachably connected thereto by screws or dowels that extend through holes indicated at 73 (Fig. 3), so that the bearings 69 and the billy roll carried thereby are detachably mounted for convenient removal from the machine, by sliding it endwise.

The cross rail 71 is supported at each end upon a nut 74 that has screw threaded engagement with a rod 75, the nuts 74 being adjustable so

that the ends of the billy roll 66 can be adjusted relative to the surfacing roll. Cushioning springs 76 are interposed between the nuts 74 and a spring seat 77 that is supported on the lower framework 10, the springs normally being of insufficient strength to hold the billy roll in its fully elevated position. The lower ends of the rods 75 are pivotally connected to crank arms 78 near the ends of a rock shaft 79 that is supported upon bearing hangers 80 which are supported from flanges on the base frame 10.

The shaft 79 is provided with a crank arm 81 by means of which it is oscillated in order to raise and lower the rod 75 and hence the billy roll 66. A piston rod 82 has an adjustably threaded connection 83 with the crank arm 81, the rod being connected to a piston 84 within a cylinder 85. Air pressure for operating the piston is supplied from a suitable source through a pressure line 86 that leads into a valve casing 87. The valve casing has an inlet port 88 and an exhaust port 89 and ports 90 and 91, which lead to the upper and lower ends of the cylinder 85. A rotary valve is contained within the valve casing and has ports 92 and 93.

In the position shown in Fig. 3, air pressure is being supplied from the line 86, past ports 88, 93 and 91, and through a pipe 94 to the underside of the piston, to raise the same. Exhaust, at this time, occurs through the ports 90, 92 and 89. The billy roll 66 is therefore held in its raised position to support a piece of work against surfacing pressure. An adjusting screw 95 is positioned to be engaged by the crank arm 81 and thereby limit the extent to which the billy roll can be moved against the surfacing roll. In case a pneumatic or other form of yieldable surfacing roll is used, the extent to which the billy roll is raised will determine the width of surfacing area in directions axially of the roll, since it will cause compression of the surfacing roll to a greater or less extent. The actual grinding pressure, however, will depend largely upon the degree of yieldability of or the air pressure in the surfacing roll. In the case of surfacing rolls which are relatively rigid, the height to which the billy roll is raised will largely determine the amount of grinding pressure.

When a sheet or strip has passed completely through the machine, the billy roll will be lowered, so that it will have no direct engagement with the surfacing roll, therefore protecting both the surfacing material from unnecessary wear or damage and also preventing the billy roll being roughened by the abrasive on the surfacing roll. The lowering of the billy roll is effected automatically by so reversing the position of the valve 87 that the valve port 42 will be brought into registry with the ports 88 and 90 and the valve port 93 brought into registry with the ports 89 and 91, in which case pressure will flow from the line 86 through the valve and a pipe 97 to the upper side of the piston 84, while exhaust from the piston will occur through the pipe 94, and the ports 91, 93 and 89.

The operation of the valve 87 is automatically effected by a pull rod 98 that is connected to the rotary element of the valve, and a lever 99. The lever 99 is pivotally mounted to a fixed support at 100 and is yieldably held in its raised position by a compression spring 101, so that when a sheet approaches the surfacing roll, the lever will be depressed, thus rocking the valve to the position shown in Fig. 3 and causing the billy roll to be raised. The ports and the cylinder 85 are of

such relative size that the billy roll will be raised to its uppermost position at about the instant the leading edge of the sheet enters the pass between the surfacing roll and the billy roll. On the other hand, as the trailing edge of the sheet or strip leaves the lever 99, the spring 101 will raise the lever to its dotted line position, so that at about the instant the trailing edge of the sheet is leaving the roll pass, the billy roll will be lowered. The billy roll and the cross rail 71 will move down under their own weight when the crank arm 81 is lowered, the springs serving to cushion such downward movement.

The air pressure beneath the piston 84, of course, yieldably holds the billy roll in work-supporting position. The degree of this yieldability will be controlled by the air pressure in the pipe 86. The pipe 86 may suitably be connected to the line 18 through a pressure regulator 96 or at some point between the pressure regulator 19 and the shaft 13. There will thus be automatic regulation of grinding pressure in addition to the automatic control of pressure in the pneumatic drum 16. This secondary automatic control of grinding pressure will be particularly useful where the surfacing roll is not of the pneumatic type.

Fig. 3a shows a modified form of device for automatically effecting movement of the billy roll 66 toward and from its operative position. In this case a solenoid coil 102 is substituted for the pneumatic cylinder 85. It will be seen that as a sheet or strip approaches the roll pass, the lever 99 will be actuated to close a switch 104, thus completing a circuit from an electric power line 105 through the solenoid coil. The core 103 will then be drawn upwardly to effect upward movement of the crank arm 81 and the billy roll.

In Fig. 7 I show a billy roll whose working area in directions axially of the roll can be changed to suit sheets of different widths. Since the surfacing roll 14 is yieldable, it will be seen that when working on sheets that are quite thin and which are of narrow width relative to the length of the billy roll, the abrasive material would often engage the surface of the billy roll adjacent to the edges of the sheet, thus not only tending to wear the billy roll, but roughening it so that it would be unsuitable for use in connection with subsequent operations on wider strips of the softer materials such as sheets of thermo-plastic material. Therefore, I mount upon the roll shaft 107 a series of sleeves 108 and 109 of different widths, these sleeves being changed to produce desired effective lengths of billy roll surface. The sleeves 108-109 are held in place by spacing collars or washers 110 and nuts 111 that have screw-threaded connection with the shaft 107. The billy roll can readily be changed in effective length by removing the pins at 73 and sliding the roll and its bearings out of the machine, as heretofore explained.

It will be understood that the surfacing roll and the sheets 67 can be moved at any desired speeds. In Fig. 3, these members are shown as moving in the same direction at the surfacing zone. The surfacing roll can, of course, be driven counter to the work, but when moved as shown in the drawing, there will be less danger of the loose abraded material interfering with the proper functioning of the apparatus, since the loose particles will be immediately carried away instead of accumulating at the entrance to the roll pass. Where, at the zone of surfacing, the roll is driven

in the same direction as the work piece moves, it will, of course, be rotated rapidly relative to the rate at which the sheets move.

Figs. 8 and 9 show guide fingers 114 and 115

- 5 mounted between the pinch rolls 42-43, and the grinding roll. These guide fingers are carried by bars 116 and 117 respectively that extend crosswise of the machine and are bolted at their ends to the supporting frames 28, by bolts 118. 10 The guide fingers are particularly useful in the surfacing of thin sheet material, since when the rear end of a sheet leaves the pinch rolls 40-41, at the entrance end of the machine, the rotation of the surfacing roll 14 in the same direction 15 as the strip movement, as indicated by the arrows in Fig. 3, will tend to push the strip ahead rapidly and bulge or bow it up between the surfacing roll and the pinch rolls 42-43. This would not only result in damage to the sheet, but there 20 would be no proper surfacing action on the rear portion thereof. Similarly-arranged guide fingers can be positioned between the pinch rolls 42 and the surfacing roll to insure proper guiding of the strips or sheets relative to the roll pass.

25 I claim as my invention:

1. Grinding apparatus comprising a roll having a sleeve of surfacing material, a shaft for the roll, bearings for the shaft, supports for the bearings, and means adjacent to one end of the roll 30 for tilting it on one of said supports as a fulcrum, to thereby lift the bearing at the other end of the roll relative to the adjacent support, whereby the said sleeve can be slid axially from the roll.

2. Grinding apparatus comprising a roll having a sleeve of surfacing material, a shaft for the roll, bearings for the shaft, adjacent to the ends of the roll, supports for the bearings, the shaft extending axially beyond its bearing at one end of the roll, and means for engaging the extended 40 portion of the shaft to tilt it on the adjacent support as a fulcrum, to thereby move the opposite end of the shaft away from its support, whereby the sleeve can be slid axially from the roll.

3. Grinding apparatus comprising a roll having a sleeve of surfacing material, a shaft for the roll, bearings for the shaft, adjacent to the ends of the roll, supports for the bearings, the shaft extending axially beyond its bearing at one end of the roll, a bracket at the extended portion of the 45 shaft, and a screw on the bracket, positioned to engage the said shaft portion, for tilting the shaft on the adjacent support as a fulcrum, to thereby move the opposite end of the shaft away from its support, whereby the sleeve can be slid axially from the roll.

4. Grinding apparatus comprising a roll having a sleeve of surfacing material, a shaft for the roll, bearings for the shaft, adjacent to the ends of the roll, supports for the bearings, the shaft extending axially beyond its bearing at one end of the roll, a driving pulley or the like on the extended 60 portion of the shaft, and a device adjacent to the pulley, for engaging the extended portion of the shaft to tilt it on the adjacent support as a fulcrum, to thereby move the opposite end of the shaft away from its support, whereby the sleeve can be slid axially from the roll.

5. Grinding apparatus comprising a frame, a surfacing roll journaled on the frame, a billy roll 70 cooperating with the surfacing roll, bearings for the billy roll, a vertically-movable support for said bearings, and means for detachably connecting the bearings to said support, the bearings and the billy roll being removable as a unit from the

frame upon disengagement of the connecting means.

6. Grinding apparatus comprising a frame, a surfacing roll journaled on the frame, a billy roll cooperating with the surfacing roll, a cross bar mounted for vertical movement in the frame and extending parallel to the said rolls, a bearing for the billy roll at each end of the cross bar, and means for detachably connecting the bearings to the cross bar, the bearings being slidably longitudinally of the said bar, for removal of the roll and its bearings when they are disconnected from the bar.

7. Grinding apparatus comprising a frame, a surfacing roll journaled on the frame, a billy roll cooperating with the surfacing roll, bearings for the ends of the billy roll, guideways in the frame slidably supporting the said bearings, for vertical movements, spring seats beneath said bearings and movable vertically therewith, fixed spring seats on the frame, cushioning springs interposed between the movable and the fixed spring seats, a rock shaft journaled in the frame, below the fixed spring seats and having a pair of crank-like extensions, a connection between each of the extensions and one of the first-named spring seats, for moving the billy roll through oscillation of said shaft, and means for rocking the said shaft to raise and lower the billy roll.

8. Grinding apparatus comprising a frame, a surfacing roll journaled on the frame, a billy roll cooperating with the surfacing roll, bearings for the ends of the billy roll, guideways in the frame slidably supporting the said bearings, for vertical movements, spring seats beneath said bearings and movable vertically therewith, fixed spring seats on the frame, cushioning springs interposed between the movable and the fixed spring seats, a rock shaft journaled in the frame, below the fixed spring seats and having a pair of crank-like extensions, a connection between each of the extensions and one of the first-named spring seats, for moving the billy roll through oscillation of said shaft, and an adjustable stop device for positively limiting movement of the last named means in a roll-raising direction.

9. Grinding apparatus comprising a frame, a surfacing roll journaled on the frame, a billy

5 10 15 roll cooperating with the surfacing roll, bearings for the ends of the billy roll, guideways in the frame slidably supporting the said bearings, for vertical movements, spring seats beneath said bearings and movable vertically therewith, fixed spring seats on the frame, cushioning springs interposed between the movable and the fixed spring seats, a rock shaft journaled in the frame, below the fixed spring seats and having a pair of crank-like extensions, a connection between each of the extensions and one of the first-named spring seats, for moving the billy roll through oscillation of said shaft, and means for vertically adjusting each of the first named spring seats relative to its cooperating fixed spring seat.

20 25 30 35 40 45 50 10. Grinding apparatus comprising a frame, a surfacing roll journaled on the frame a billy roll cooperating with the surfacing roll, bearings for the ends of the billy roll, guideways in the frame slidably supporting the said bearings, for vertical movements, spring seats beneath said bearings and movable vertically therewith, fixed spring seats on the frame, cushioning springs interposed between the movable and the fixed spring seats, a rock shaft journaled in the frame, below the fixed spring seats and having a pair of crank-like extensions, a connection between each of the extensions and one of the first-named spring seats, for moving the billy roll through oscillation of said shaft, and means actuated through movement of work material to and from the pass between said rolls, to lower and raise the billy roll.

11. Grinding apparatus comprising a frame, a surfacing roll journaled on the frame a billy roll cooperating with the surfacing roll, bearings for the ends of the billy roll, guideways in the frame slidably supporting the said bearings, for vertical movements, a rock shaft journaled in the frame below the bearings and having a pair of crank-like extensions, lifting members supporting the bearings on the extensions, means for vertically adjusting the planes of engagement between the bearings and said members, adjustable means positively limiting upward movement of each of said members, and yieldable operating means for rocking the shaft in a direction to raise the billy roll bearings.

ALFRED E. HAMILTON.
